UNITED STATES PATENT OFFICE

117,913

DESIGN FOR A DISPLAY STAND FOR HOSIERY

Samuel Sobel, New York, N. Y.

Application October 2, 1939, Serial No. 87,479

Term of patent 14 years

To all whom it may concern:

Be it known that I, Samuel Sobel, a citizen of the United States, residing in the city, county, and State of New York, have invented a new, original, and ornamental Design for a Display Stand for Hosiery, of which the following is a specification, reference being had to the accompanying drawing, forming part thereof.

I claim:

The ornamental design for a display stand for hosiery, as shown.

SAMUEL SOBEL.
